UNITED STATES PATENT OFFICE

LESTER L. COLLINS, OF FRANKLIN, PENNSYLVANIA, ASSIGNOR TO CHICAGO PNEUMATIC TOOL COMPANY, OF NEW YORK, N. Y., A CORPORATION OF NEW JERSEY

APPARATUS FOR THE SPEED REGULATION OF ENGINES

Application filed March 30, 1929. Serial No. 351,253.

This invention relates to the regulation of engines in response to the load or demand upon the same. While capable of general application it has been developed with particular reference to engine-driven pumps and compressors, especially the steam-driven type in which the speed of the engine is controlled by adjusting or varying the steam cut-off.

One object of the invention is to provide a simplified and improved form of control mechanism. Another object is to combine the usual speed governor with load responsive apparatus in a single regulator device. Other objects will be apparent from the detailed description which follows.

In order to illustrate the invention one concrete embodiment thereof is shown in the accompanying drawings in which:

Fig. 1 is an end elevational view of the regulator apparatus indicating diagrammatically a portion of the engine for driving a pump or compressor; and

Fig. 2 is a side elevational view partly broken away and partly in section of the regulating apparatus shown in Fig. 1.

The embodiment of the invention chosen for the purpose of illustration indicates diagrammatically at A a portion of a steam engine having a shaft *a* arranged in any known or desired manner to vary the cut-off of the valves, engine A being arranged to drive a pump or compressor (not shown). The regulating apparatus is supported upon a base 3 forming a part of the engine frame and comprises a casing 4 in which is slidably mounted for reciprocatory movement a rack 5 which operates a pinion 6 on shaft 7 which carries a sprocket or wheel 8 for operating a chain or belt 9 encircling a sprocket or wheel *a* on engine control shaft *a*. An idler 10 is provided to adjust the tension of belt or chain 9.

The movement of rack 5 is controlled by hydraulic means which may take the form of the well-known Mason regulator in which a piston 11 moves in a cylinder 12 in response to fluid admitted to and vented from the cylinder by a pilot valve 13, piston 11 being directly connected to rack 5 by rod 14. Pilot valve 13 is secured to a floating lever 15 which is pivoted at one end to a bell crank 16, the

angular position of the latter being automatically determined by a cam slide member 17 secured to piston rod 14 and moving with the latter. Bell crank 16 and cam slide 17 provide compensating means for returning pilot valve 13 to neutral position after the movement of floating lever 15.

Means responsive both to the speed of the engine and to the demand upon the pump or compressor operated thereby are provided for controlling the engine speed through the regulator apparatus and connections heretofore described. Both such means are arranged independently to actuate the floating lever 15 which controls the position of pilot valve 13. The speed responsive means are mounted upon a bracket 18 projecting from casing 4 above lever 15 and may be of any suitable or desired type. A fly ball governor indicated generally at B is illustrated which may be driven from the engine shaft by a belt *b*, the governor having a rod 19 extending downwardly therefrom and preferably extending through a perforation in lever 15. Rod 19 has a fixed stop 20 in the form of a washer or shoulder above lever 15 and an adjustable stop which may take the form of a nut 21 disposed beneath lever 15. A coil spring 22 interposed between stop 20 and lever 15 yieldingly holds the latter in engagement with stop 21 but permits upward movement of the lever.

The pressure responsive means include an arm 23 pivotally mounted in the lower portion of casing 4 for limited movement. Pressure fluid from the receiver (not shown) supplied by the pump or compressor is admitted through a pipe 24 beneath a diaphragm 25 having a plunger 26 engaging arm 23 to move the latter upwardly. Upward movement of the arm 23 is opposed by adjustable weights 27 and by an adjustable stabilizer which includes a rod 28 pivoted to arm 23 and having a sleeve extension 29 within which telescopes a rod 30 pivoted to a post 31 projecting from bracket 18. A spring 32 encircles rod 30 between sleeve 29 and adjusting nut 33 and upward movement of arm 23 will be increasingly resisted as spring 32 is compressed.

The connection between arm 23 of the pressure responsive means and lever 15 is such that upward movement only of arm 23 is transmitted to lever 15 and this movement is in the direction permitted by spring 22 on operating rod 19 of governor B. The connection comprises a rod 34 pivoted to arm 23 and carrying a sleeve member 35 into which a rod 36 pivotally secured to lever 15 telescopes with a free sliding fit. The length of rod 36 is adjustable so that the same may be arranged to engage rod 34 when arm 23 begins its upward movement.

From the above it will be apparent that the control apparatus for the engine is simplified by causing both the over-speed governor and the pressure responsive apparatus to operate through one and the same hydraulic regulator thereby providing an exact and highly flexible adjustment of the control shaft of the engine, that the connections are such that the pressure and speed governors may operate independently, and that the apparatus is simple, compact, positive in operation and conveniently arranged for adjustment and repairs.

While the invention has been herein shown and described in what is now considered to be a preferred form, it is to be understood that the invention is not limited to the specific details thereof, but covers all changes, modifications and adaptations within the scope of the appended claims.

I claim as my invention:

35 1. Regulating apparatus for the driving engine of a pump or compressor comprising actuating means for the control member of the engine, hydraulic means for operating said actuating means including a pilot valve, 40 a lever for actuating said valve, compensating means for restoring said valve to neutral position after movement of said lever, speed responsive means connected to said lever to move the latter in opposite directions, and 45 pressure responsive means having a loose connection to the latter so as to move the same in one direction only.

2. Regulating apparatus for the driving engine of a pump or compressor comprising 50 actuating means for the control member of the engine, hydraulic means for operating said actuating means including a pilot valve, a lever for actuating said valve, compensating means for restoring said valve to neutral 55 position after movement of said lever, speed responsive means connected to said lever to move the latter in opposite directions, and pressure responsive means having a loose connection to the latter so as to move the same in 60 one direction only, the connection between said lever and said speed responsive means being yielding in the direction in which said lever may be moved by said pressure responsive means.

65 3. Regulating apparatus for the driving

70 engine of a pump or compressor comprising actuating means for the control member of the engine, hydraulic means for operating said actuating means including a pilot valve, a lever for actuating said valve compensating means for restoring said valve to neutral position after movement of said lever, speed regulating means having a rod providing stops on either side of said lever, a spring engaging one of said stops and yieldingly maintaining said lever in engagement with the other of said stops, a weighted arm, means responsive to the pressure developed by said pump or compressor for moving said arm against the weights thereon, and a loose connection between said arm and said lever for effecting movement of the latter in the direction permitted by said spring.

75 4. Regulating apparatus for the driving engine of a pump or compressor comprising actuating means for the control member of the engine, hydraulic means for operating said actuating means including a pilot valve, a lever for actuating said valve, speed responsive means having a rod extending through a perforation in said lever and provided with stops on opposite sides thereof, a coil spring encircling said rod and engaging one of said stops and yieldingly maintaining said lever against said other stop, a weighted arm, means responsive to the pressure developed by said pump or compressor for moving said arm against the weights thereon, and telescoping members extending from said lever and said arm respectively and arranged to transmit movement of the latter in the direction permitted by said spring.

80 5. Regulating apparatus for the driving engine of a pump or compressor comprising actuating means for the control member of the engine, hydraulic means for operating said actuating means including a pilot valve, a lever for actuating said valve, compensating means for restoring said valve to neutral position after movement of said lever, a weighted arm, means responsive to the pressure developed by said pump or compressor for moving said arm against the weights thereon, a loose connection between said arm and said lever whereby movement of the latter is effected only when said arm moves toward said lever, and adjustable means for yieldingly resisting movement of said arm toward said lever.

85 6. Regulating apparatus for the driving engine of a pump or compressor comprising actuating means for the control member of the engine, hydraulic means for operating said actuating means including a pilot valve, a lever for actuating said valve, speed responsive means having a rod extending through a perforation in said lever and provided with stops on opposite sides thereof, and a coil spring encircling said rod and engaging one of said stops and yieldingly maintaining said
